US00D507263S

(12) **United States Design Patent** (10) Patent No.: **US D507,263 S**
(45) Date of Patent: **** Jul. 12, 2005**

(54) **ADAPTER**

(75) Inventor: **Hisanori Narita**, Tokyo (JP)

(73) Assignee: **Sony Corporation**, Tokyo (JP)

(**) Term: **14 Years**

(21) Appl. No.: **29/193,128**

(22) Filed: **Nov. 5, 2003**

(51) LOC (8) Cl. **14-03**

(52) U.S. Cl. **D14/240**

(58) Field of Search **D14/140, 149, D14/142, 150, 240, 251, 409, 358, 155, 432; 379/426, 449, 93.14, 93.15, 26, 427, 441, 424, 443, 422; 455/569, 570; D10/107**
